(57) CLAIM

The ornamental design for a pair of gloves, as shown and described.

DESCRIPTION

FIG. 1 is an elevational palm-side view of pair of gloves according to the present invention;

FIG. 2 is an elevational backhand view of the gloves of FIG. 1 according to the present invention; and,

FIG. 3 is an elevational palm-side view of the gloves of FIG. 1 being worn by a user, according to the present invention. The partial human figure shown in broken lines illustrates the environment in which the design is used and forms no part of the claim.
